DESIGN FOR A PIANO OR THE LIKE

William Zaiser, Rockville Centre, N. Y., assignor
to The Rudolph Wurlitzer Company, Cincinnati,
Ohio, a corporation

Application May 17, 1940, Serial No. 92,432

Term of patent 7 years

To all whom it may concern:

Be it known that I, William Zaiser, a citizen
of the United States, residing at Rockville
Centre, in the county of Nassau and State of
New York, have invented a new, original, and
ornamental Design for a Piano or the like, of
which the following is a specification, reference
being had to the accompanying drawing, forming
part thereof.

In the drawing: Fig. 1 is a perspective view
of a piano or the like, showing my new design;

and Fig. 2 is a fragmentary front elevational
view thereof, the legs and lower frame of the
piano being shown broken away.

The dominant feature resides in the surface
decoration at each side of the upper panel of
the piano, said surface decoration simulating book
backs, as shown.

I claim:

The ornamental design for a piano or the like,
as shown and described.

WILLIAM ZAISER.
